UNITED STATES PATENT OFFICE.

PAUL WENTWORTH WEBSTER, OF PELHAM MANOR, NEW YORK, ASSIGNOR TO FERRY & WEBSTER INCORPORATED, OF ELIZABETH, NEW JERSEY, A CORPORATION OF NEW JERSEY.

OXIDIZABLE OIL.

No Drawing.

Application filed October 3, 1918. Serial No. 256,738.

To all whom it may concern:

Be it known that I, PAUL W. WEBSTER, of Pelham Manor, in the county of Westchester, and in the State of New York, have 5 invented a certain new and useful Improvement in Oxidizable Oils, and do hereby declare that the following is a full, clear, and exact description thereof.

This invention relates to an article of 10 manufacture, an oxidizable oil.

The object of the invention is to provide a vegetable oil which is particularly adapted as a froth-producing material in the flotation process of recovering metals.

15 In the manufacture of paints and varnishes, various types of drying oils such as linseed oil, tung oil, china wood oil and soya bean oil are boiled and heated with resins, gums, pigments and other materials 20 to form the finished products. In these heating operations, the fumes are driven off from the boiling and heating kettles which consist of vapors and volatile oils and some comparatively permanent gases. These fumes 25 heretofore have been exhausted through stacks and were a great source of annoyance to the community around the paint and varnish factory because they were very noxious and gave a disagreeable deposit. Examination 30 of these fumes has shown that they contain an oil distillate formed from the drying oils which may be separated from the other constituents of the fumes by condensation. This distillate is an oxidizable oil which is 35 well adapted for use in the flotation process of recovering metals and for other purposes.

To recover the oxidizable oil, the fumes being driven off from the heating kettles are 40 collected in fume-collectors and passed through a series of condensers. The condensers may consist of tubes which are cooled by means of air, cooling liquids, refrigeration materials, or a combination of two or more of these. The distillate from 45 the drying oils is oxidizable and air may be led into the condensing tubes to oxidize the fumes while they are in the hot state so that the distillate will be oxidized to a greater or less extent when it is condensing. In accordance 50 with the amount of air admitted to the condensing tubes, a greater or smaller amount of the distillate will be completely oxidized when it is recovered from the con-

densing tubes and may, therefore, consist of an oxidized distillate or a mixture of oxidized and non-oxidized distillate.

The method of and apparatus for recovering the improved distillate of drying oils is shown and described in my copending application for a process of and apparatus for 60 treating volatile constituents of fatty oils, gums, resins and like materials Serial No. 351,825, filed January 16, 1920. Reference is hereby made to said application for a detail description of the method of and apparatus for recovering the improved distillate.

The improved oil distillate will condense at temperatures below 75° F., and a relatively larger proportion of the fume will be condensed as the temperatures are carried 70 down to 0° F. and lower. The distillate which has been condensed at temperatures below 75° F. down to 32° F. is a comparatively stable liquid and below temperatures of 32° F. the distillate is a semi-solid. The 75 maximum boiling point of the distillate is not materially above 75° F.

The stable liquid distillate at temperatures between 35° and 60° F. is an oxidizable vegetable oil which may be used with certain kinds of minerals in the flotation separation process to produce a light foam or froth for carrying the metallic particles and sulfides in the minerals. The agitation of the oil distillate particularly by means of 80 air as well as by mechanical agitation, serves to break up the oil to form a comparatively light and thick froth which is particularly adapted for carrying certain types of metallic and sulfide particles.

The oil distillate which is called "dioxenated oil," may be oxidized by means of air or other oxidizing agents so that it can be converted into a semi-solid or solid condition 85 at ordinary temperatures.

The preferred form of the invention having been thus described, what is claimed as new is:

1. An oxidizable oil comprising a distillate of an air-drying fatty oil which has a condensing point below 75° F. and congeals to a semi-solid condition at a temperature below 32° F.

2. An oxidizable oil comprising a distillate of linseed oil which has a condensing point below 75° F.

3. An oxidizable oil comprising a partially oxidized distillate of an air-drying fatty oil.
4. An oxidizable oil comprising a partially oxidized distillate of linseed oil.
5. An oxidizable oil comprising a mixture of oxidized and non-oxidized distillates of linseed oil.
6. An oxidizable oil comprising a distillate of an air-drying fatty oil which is

semi-solid at temperatures below 32° F. and 10 has a condensing point below 75° F.

In testimony that I claim the foregoing I have hereunto set my hand.

PAUL WENTWORTH WEBSTER.
